UNITED STATES PATENT OFFICE

163,876

TEXTILE FABRIC OR SIMILAR ARTICLE

Rockwell Kent, Au Sable Forks, N. Y., assignor to Charles Bloom Inc., New York, N. Y., a corporation of New York

Application February 15, 1951, Serial No. 14,220

Term of patent 3½ years

(Cl. D92—1)

To all whom it may concern:

Be it known that I, Rockwell Kent, a citizen of the United States, and residing at Au Sable Forks, Essex County, New York, have invented a new, original, and ornamental Design for a Textile Fabric or Similar Article, of which the following is a specification, reference being had to the accompanying drawing, forming a part hereof.

The figure of the drawing is a plan view of a piece of textile fabric, showing my new design. The design unit is outlined by broken lines, which unit is repeated over the textile fabric as indicated.

I claim:

The ornamental design for a textile fabric or similar article, as shown and described.

ROCKWELL KENT.
